UNITED STATES PATENT OFFICE.

EDWARD OAKMAN HOOD, OF WELLESLEY HILLS, MASSACHUSETTS.

WELTING.

1,204,769.

Specification of Letters Patent. Patented Nov. 14, 1916.

Application filed January 8, 1916. Serial No. 69,805.

To all whom it may concern:

Be it known that I, EDWARD OAKMAN HOOD, a citizen of the United States, residing at Wellesley Hills, in the county of Norfolk and State of Massachusetts, have invented new and useful Improvements in Welting, of which the following is a specification.

The object of the present invention relates to 10 welting, or a welt strip for use in shoe-making.

The object of the invention is to provide welting having the particular useful qualities and advantages hereinafter particularly 15 described.

The precise nature of the invention fully appears from the following description of a particular embodiment thereof.

In the drawings, Figure 1 is a perspective 20 view of a welt strip embodying my invention. Fig. 2 is a longitudinal side view of a fragment of such strip. Fig. 3 is a cross section on line 3—3 of Fig. 1.

The improved welting which I have produced by the present invention is two ply 25 consisting of a body ply *a* and a face ply or veneer *b*. Each ply is made as welt strips have heretofore been made, of narrow strips or pieces placed end to end to make a continuous strip of indefinite length, the joints 30 between the successive pieces being beveled or scarfed and cemented. The two plies so made of pieces joined end to end are placed one upon the other and cemented or otherwise 35 securely joined throughout their entire length. In so connecting one ply to the other care is taken that the joints *c*, *c*, etc., between the pieces of one ply are intermediate the joints *d*, *d*, *d*, etc., of the other ply.

It will be noted that the joints of the 40 two plies are oppositely inclined; that is, that while the joints *c* between the sections of the lower ply are inclined upward from right to left, when viewed as shown in the drawings, the joints *d* in the top ply are 45 downwardly inclined from right to left when viewed in the same manner. Thereby the piece on the left hand side of each joint overlaps the piece at the right hand side of the joint in each ply. This construction 50 and arrangement of the joints is a feature of much importance in my invention for this reason. Welt strips are grooved and beveled before being incorporated into 55 shoes. In being operated upon to this end the strips are pulled past knives or other

cutting tools in contact with a guard or gage. It is highly important that the joints in the body ply should pass the grooving and beveling knives in such direction that the thin edge of the outer scarf is the last part of the joint to pass the knives, for, if the direction of feeding were the opposite of this, the knives would have a tendency to dig into the joint, pull up the overlapping scarf, and either tear open the joint or cut too deeply, gouging or tearing out a part of the strip and weakening it. That is, referring to Fig. 2, the strip must be fed past the knives in the direction of the arrow shown in said figure, assuming that the knives are arranged to act on the under side of the ply *a*. In the single ply welts, however, this mode of feeding has the effect of bringing the scarf on the opposite side of the joint point first toward the gage or guard, with the effect that if the joint is not practically perfect, the gage will have a tendency to bend back and pull the overlapping scarf and open the joint to a greater or less extent. With the two ply strip, the outer ply overlying the joints in the body ply prevents such joints from being pulled open by the gage and guard members of machines in which the welting is operated upon, while the arrangement of the joints *d* on this ply on the opposite inclination to the joints of the body ply, makes it impossible for such gages or scarfs to pull open these joints either, but causes them rather to smooth down and compact the joints.

I prefer to make what I call the body ply to furnish the main strength that is needed by the welting, using the outer or surface ply to give an attractive finish and appearance, besides performing the office above described in protecting the joints of the body ply. By thus using two plies I am able to reduce the cost of manufacture to less than that required for the single ply welts as heretofore made, besides producing a superior article. I may use split leather for the body ply, which is much less expensive than grain leather of the thickness required for welting. This statement applies even to splits from the best part of the hide, of which the leather is better and stronger than in those parts of the hide, namely the shoulders, from which welting is usually taken. Thus one useful result of my invention is to permit the use of better leather than is commonly used for welting at less cost.

The outer or face ply *b* is of grain leather which is either so thin or is of such a grade or quality of leather that it is much less expensive than grain leather having the full thickness of welting. Without intending to limit the invention in regard to the material for this ply, I may say that I have found sheepskin to be very desirable and satisfactory. Sheepskin by itself is not suitable for any part of a shoe on account of being too soft and too stretchy; but when built into a welt strip as a veneer to the body, it has exactly the qualities required. It is sufficiently soft to enable the stitches which attach the outer sole to sink deeply into it, and later to receive deeply the impressions of the fudge wheel or indenting wheel, which is later used to impress and hide the stitches. Indeed with the use of this material it is possible to conceal such stitches almost completely. Sheepskin has a good grain and presents a smooth glossy finished appearance after the stitches of the outer seam have been concealed by the indentations of the fudge wheel. It is for the purpose of this appearance primarily that welting has heretofore always been made of grain leather, and for which I provide a grain leather face ply in my composite welting. Welting used with the flesh side outward, or made from split leather from which the grain has been removed, is rough and furry, particularly after sewing of the outer seam and indenting it with the fudge wheel, whereby shoes having such welts are not acceptable to the trade.

Another advantage of sheepskin for the purpose described is that it is so very flexible and stretchy that it can be sharply bent and greatly stretched, as in passing around the toes of sharply pointed shoes, without breaking or cracking; at the same time it is firm, whereby the welter, which term designates the workman in shoe factories who applies welts to shoes, is able to accomplish his work more easily and rapidly. The face ply also strengthens the joints in the body ply and aids them to resist the tendency to open when bent, as at the toe of a shoe. It will be observed, however, that although sheepskin is a highly desirable material for the face ply of the welt, and is preferred for many purposes, it is not the only useful or available material.

My invention contemplates welting made from a body ply of split leather and a face ply of grain leather, of whatever grade or quality or kind the grain leather may be. Among other sources for the grain leather may be named machine buffing, which is a skiving, about as thick as heavy paper,

which is removed from the grain side of leather, preparatory to the use of the leather for various purposes. However I may use any kind of light grain leather which is not thick enough in itself to have the strength required for welting, from whatever source such leather may be derived.

I am aware that heretofore welting, as well as many other leather manufactures, including power belts, have been made of two plies, and also that in such manufactures or constructions, the plies have been so arranged that the joints between the sections of one ply have come intermediate similar joints in the adjacent ply. I therefore do not claim as my invention the fundamental idea of a two ply welt strip. What I do claim is the particular character of such strip having the purposes and useful qualities hereinbefore described, and embodying the characteristics pointed out in the appended claims.

What I claim and desire to protect by Letters Patent therefore is:

1. A two ply welt strip consisting of a body ply of split leather in which the strength of the welt is mainly contained, and a face ply of grain leather united to the body ply on one surface only thereof. 90

2. A welt strip comprising a body ply and a face ply, the body ply being of material having great strength but lacking the grain surface of leather, and the face ply being of grain leather on its outer surface and being attached to the body ply on one surface only thereof. 95

3. A welt strip comprising a body ply and a face ply, the body ply being of material having great strength but lacking the grain surface of leather, and the face ply being of grain leather on its outer surface, each of said plies being composed of sections having their adjoining ends scarfed and lapped one over the other, such scarfed joints of the two plies being relatively oppositely inclined. 100

4. A welting comprising a body ply of a relatively strong split leather lacking grain surface, and a face ply of relatively soft and flexible leather having its grain surface, and being attached to one face only of the body ply with its grain surface outward. 110

5. A welting comprising a body ply of a relatively strong split leather lacking grain surface, and a face ply of sheepskin having its grain surface intact, and being attached to one face only of the body ply with its grain surface outward. 115

In testimony whereof I have affixed my signature.

EDWARD OAKMAN HOOD.
